FLEXIBLE PRESSING MACHINE PAD

George W. Bristol, New York, N. Y.

Application May 3, 1939, Serial No. 271,470

14 Claims. (Cl. 38—66)

The purpose of this invention is to provide improvements in yielding metallic underpadding, for laundry and pressing machines, that consists of a plurality of relatively small floating units spaced apart from and resiliently held above a base, thereby increasing the flexibility of the pad, and at the same time providing a dry heat retaining chamber under the pad. These improvements also make it possible to provide a pad that will operate efficiently on curved or straight surfaces, and permit depression to substantially any degree to accommodate buttons, seams, or the like.

This invention is an improvement over my prior Patent Number 1,897,836, in that the holding members extending upward from the base are inclined outward, the caps are readily removable, and the bases are mounted in a network of transverse and longitudinal strips providing an interwoven base adjustable and bendable in all directions. Other improvements are in the shape and construction of the cap which, in combination with the inclined upwardly extending supporting members, makes it possible to provide a relatively floating movement with the entire cap adapted to be moved straight downward or inward, or at any angle up to approximately 60 degrees, and these movements are obtained without binding in the mounting means or binding of one cap against another.

The prior patent provides a plurality of comparatively independent yielding caps held by projections on the lower side extending into grooves in upright members from a base; however, it was found that this construction permitted engagement of the corners of the caps when the caps were mounted comparatively close together, and it was practically impossible to remove the caps from the bases without destroying them. Other patents have been granted on similar devices, however all of these disclose caps mounted on channel shaped members or in some form of a continuous base member that is substantially impossible to place over a curve with any degree of efficiency, and, while these other devices do provide yielding caps, they do not provide a relatively floating cap, or a cap that is yieldable in all directions without striking or binding against an adjoining cap or upon the mounting means, and, therefore, these devices have been found objectionable because with expansion and contraction the binding is increased so that they stick or do not yield, and then the tremendous pressure on the ironing pad breaks the caps, and also the mounting means.

The object of the invention is, therefore, to improve the construction of resilient or yielding metallic pads of this type so that the caps may yield or move downward, straight, or at any angle without one cap engaging or binding against an adjoining cap, and with the mounting means so shaped that there can be no binding between the cap and mounting means.

Another object is to provide mounting means for flexible or yielding caps of this type which is adapted to be used either on a flat or straight surface, or around a curve or on any combination of curves and flat surfaces.

Another object is to provide a yielding cap for the underpadding of laundry and pressing machines which permits circulation of air or steam under the pad, thereby providing a heat retaining area or space under the pad.

Another object of the invention is to provide a cap for resilient padding which is sufficiently ventilated to permit moisture from the cloth padding to escape into the area below the caps where it will be evaporated by the heat of the buck of the machine.

Another object is to provide mounting means for yielding metallic underpadding which facilitates assembling and makes it possible to obtain substantially any combination of pads.

A further object is to provide mounting means for yielding metallic pads in which the caps there- may readily be removed and replaced.

And a still further object is to provide resilient metallic padding for laundry and pressing machines which is flexible and substantially floating, and which is also of a simple and economical construction.

With these ends in view the invention embodies a resilient metallic padding comprising a plurality of caps having relatively large openings in the surfaces thereof, substantially vertical posts in which the caps are slidably mounted, springs resiliently holding the caps upward, and a network of material in which said posts may be mounted.

Other features and advantages of the invention will appear from the following description taken in connection with the drawings, wherein:

Figure 1 is a plan view of a section showing a corner of the pad with parts assembled, parts omitted, and parts broken away.

Figure 2 is an end view illustrated in elevation showing a portion of the pad with parts omitted and parts broken away.

Figure 3 is a detail showing a part section

through the pad, showing the caps in elevation with the cross strips in section.

Figure 4 is a detail showing the base strip of the pad.

5. Figure 5 is a side elevation of the strip shown in Figure 4.

Figure 6 is a plan view of the binding strip of the pad.

10. Figure 7 is a side elevation of the strip shown in Figure 6.

Figure 8 is a plan view of one of the end caps of the pad.

Figure 9 is a similar view of a center cap of the pad when the pad is used on a curve.

15. Figure 10 is a view showing the intermediate caps of the pad.

Figure 11 is a side elevation of the cap shown in Figure 10.

20. Figure 12 is an end elevation of the cap shown in Figure 10.

Figure 13 is a plan view of the stud upon which the caps are mounted.

Figure 14 is an end view of the stud.

25. Figure 15 is an end view showing a side elevation of the stud.

Figure 16 is a view showing a section of a pad positioned on a curve, with some of the caps indicated in the depressed position by dotted lines.

30. Figure 17 is a similar view showing a section of the pad on a straight base, with the positions of some of the caps distorted, and with one cap shown in the assembling position.

Figure 18 is a similar view looking toward the open sides of the caps.

35. Figure 19 is a plan view of a corner of a pad formed of the strips illustrated in Figure 22 with parts omitted and parts broken away.

Figure 20 is a detail showing a portion of one of the strips illustrated in Figure 6 assembled over one of the strips illustrated in Figure 22.

40. Figure 21 is an end view of a portion of the pad illustrated in Figure 19.

Figure 22 is a plan view showing an alternate design of a strip, as indicated in Figure 4, in 45 which the uprights of the studs are formed integral with the strip.

Figure 23 is a view showing a cross section through the strip shown in Figure 22.

Figure 24 is a side elevation of the strip shown 50 in Figure 22.

Figure 25 is a detail showing a longitudinal section through a portion of the strip shown in Figure 22 on line 26—25 of Figure 22.

55. In the drawings the device is shown as it may be made, wherein numeral 1 indicates the cap, numeral 2, the cap studs, numeral 3, the longitudinal strips, numeral 4, the transverse strips, and numeral 5, the springs.

60. The caps 1 are vertically slidable on posts of the studs 2, and the studs are held in openings in the members 3 and also in recesses in the members 4, and the caps are resiliently held upward by the springs 5. In assembling the pads the strips 3 are placed over the strips 4 with the studs 2 placed over these strips and with the vertical posts thereof extending upward through them so that this part of the device lies upon the base as an interwoven mat with any part thereof readily replaceable. The springs are then placed upon the strips 3 and the caps placed upon the extensions of the studs 2 by placing the projections thereof through notches in the upper ends of the studs with the caps held in substantially an angle of 60 degrees, as shown at the

end of Figure 10, and the caps may be readily removed in the same manner.

It is preferable to make the caps 1 as shown in Figure 10, in which the central section 6 forms the top, and at the ends are sections 7 which bend downward as shown in Figure 11, and at one side is a section that bends downward so that tongues 8 extending outward therefrom will extend under the top 6 of an adjoining cap as shown in Figure 1. The first row of caps, however, which are indicated by the numeral 9 and shown in Figures 8 and 9, are provided with tongues 10 having openings in them adapted to lock over projections on the interior of adjoining caps as shown in Figure 1. At the ends of the members 7 are sections 11 which will bend inward as shown in Figure 11. These sections 11 extend into recesses 12 on the interior of posts 13 extending upward from the plate 2 forming the base. The upper ends of the posts are 20 formed by plates 14 having slots 15 through which the parts 11 pass when assembling the cap on the base with the cap held as shown in Figure 17. The lower ends of the springs 5 are held between the posts, and the upper ends are held 25 between projections 16 extending downward from the plate 6 and punched from one of the openings 17 therein, which are provided in the upper surfaces 6 of the caps. When assembling the device, the strips 3 and 4 are attached to end strips 18 by eyelets as shown in Figure 1, and similar strips are placed at the opposite end of the pad.

The strips 4 are made as shown in Figures 4 and 5 in which the edges thereof are provided 35 with recesses 19 which correspond with the posts 13, and the members 3, shown in Figures 6 and 7, and which are formed with openings 20, are placed across the strips 4 with the openings 20 corresponding with the recesses 19, and also of 40 the same shape as the posts 13, so that the posts may be placed upward through these recesses with the plates 2 below the strips 4. The edges at the ends of the strips 3 are bent downward forming flanges 21 which are the same length as 45 the thickness of the plates 2, so that all of the parts will rest evenly upon a base member. The strips 3 may be used continuously or alternated with a strip for every other row of caps, and the spaces on the strips 4 between the strips 3 may be 50 provided with bosses 22 for holding the springs. The strips 3 are provided with circular bosses 23 over which the springs 5 are placed, and it will be noted that the lower ends of the springs are, therefore, located by the bosses 22 and 23, where- 55 as the upper ends are held between the projec- tions 17. This provides a complete pad, and with the respective parts in place, it will be noted that the caps will be resiliently held upward with their upward movement limited by the engagement of 60 the members 10 and 11, with the plates 14, and with the downward movement limited by the closing of the spring.

It will be understood that the distance between the recesses 19 may vary, and, in the design 65 shown, the distance between the recesses having a flat surface is $\frac{3}{16}$ ", whereas this gradually diminishes to as small as $\frac{1}{16}$ " as the strips extend over a curve, and this dimension is materially decreased when the curve becomes comparatively 70 sharp, as shown in Figure 16. It is appreciated, however, that the distance between the centers of these recesses which control the distances between the upper surfaces of the caps may be varied according to different radii.

The bases 2 of the studs are provided with indentations 24 forming spacing ridges extending downward therefrom, and the strips 3 are formed with indentations 25 extending downward the same depth as the ridges 24, spacing the strips from a base and locating the strips 4 therebetween.

An alternate arrangement is shown in Figures 22, 23 and 24, in which the posts, which are indicated by the numeral 26, are made integral with strips 27 which correspond with the strips 4, and the strips 3 are placed transversely across the strips 27 with the openings 20 corresponding with the posts 24, and it will be noted that the strips 3 may be used continuously or may be spaced to correspond with every other cap, and with the strips alternately spaced to correspond with every other cap it is necessary to provide bosses 28 on the strips 27 between the strips 3. In this design the strips 25 are similar to and substantially of the same size as the strips 4, and the posts 26 are formed from the material of the strips so that they extend directly upward similar to the posts 13. The upper ends of these posts are provided with notches 9 which are similar to the notches 15, and the caps may, therefore, be assembled on the posts in a similar manner. The strips 27 extend longitudinally of the pad, and these are held together by the strips 3 positioned perpendicularly thereto.

It will be understood that other changes may be made in the construction without departing from the spirit of the invention. One of which changes may be in the use of other means for mounting or holding the bases or posts upon the bed of a machine, another may be in the use of other means for assembling the caps on the bases, and still another may be in the use of other means for compensating for the different dimensions caused by placing the device on a curved surface.

The construction will be readily understood from the foregoing description. In use the device may be provided as shown and described, and it will be noted, particularly in Figures 17 and 18, that, with the caps of the pad assembled in this manner, and particularly with this rectangular type of construction, each individual cap may be pressed downward to substantially any position without binding between the caps or between the caps and the supports therefor. The dotted lines indicate the normal position of the caps, whereas the full lines indicate the extreme angles to which the caps may be pressed downward by buttons, hems, seams, or the like. It will be noted, as indicated by the dotted lines, that the caps may be pressed straight downward, or one corner of the cap may be pressed all of the way downward, or several caps may be pressed downward at the same time without any possibility whatever of one cap engaging another and of one cap binding against the other, and also with substantially no possibility whatever of the caps binding upon the studs. It will be understood that the springs pass upward inside of the caps, thereby providing the greatest possible spring length and flexibility in the limited space occupied by the device.

It will be noted in Figure 17 that even caps on a curve may be pressed straight downward, or only one corner or side may be pressed downward, and even in this position there will be no possible binding of the caps against each other or against the supporting means. This particular arrangement of caps with the supporting

members provides substantially a floating cap which, at the same time, has sufficient force to sustain a considerable load, and this force may be varied at will depending upon the size of wire used in the springs.

5

Having thus fully described the invention, what I claim as new and desire to secure by Letters Patent is:

1. A resilient pad comprising a plurality of individual units each independently resilient, and all individually mounted on transverse and longitudinal strips, in which each unit is provided with a cap, means resiliently holding said cap upward, and grooved posts with projections from the cap extending into said grooves limiting the upward movement of the cap, said posts tapering upward providing relative flexibility of movement of said cap.

2. A resilient pad comprising a plurality of individual units each independently resilient, and all individually mounted on transverse and longitudinal strips, in which each unit is provided with a cap, means resiliently holding said cap upward, and grooved posts with projections from the cap extending into said grooves, limiting the upward movement of the cap, and in which said limiting means tapers outward and upward, providing flexibility in the tilting movement of said cap in all directions.

3. A resilient pad comprising a plurality of individual units each independently resilient, and all individually mounted on transverse and longitudinal strips, in which each unit is provided with a cap, means resiliently holding said cap upward, grooved posts with projections from the cap extending into said grooves limiting the upward movement of the cap, and in which said limiting means tapers outward and downward, providing flexibility in the tilting movement of said cap in all directions, and said resilient means comprising a spring extending upward into said cap.

4. A resilient pad comprising a plurality of individual units each independently resilient, and all individually mounted on transverse and longitudinal strips, in which the transverse strips are formed with recesses in the sides thereof, and the longitudinal strips with openings corresponding with said recesses, and base members with posts extending upward through said recesses and openings providing mounting means for springs providing the resilient members of said units.

5. A resilient pad comprising a plurality of individual units each independently resilient, and all individually mounted on transverse and longitudinal strips, in which the transverse strips are formed with recesses in the sides thereof and the longitudinal strips with openings corresponding with said recesses, and the units include base members with posts extending upward through said recesses and openings providing mounting means for resilient members of said units, said posts sloping outward and upward.

6. A resilient pad comprising a plurality of individual units each independently resilient, and all individually mounted on transverse and longitudinal strips, in which the transverse strips are formed with recesses in the sides thereof, and the longitudinal strips with openings corresponding with said recesses, and the units include base members with posts extending upward through said recesses and openings providing mounting means for springs providing the resilient members of said units, said posts sloping upward and

65
70
75

outward and having caps vertically slideable thereon.

7. A resilient pad comprising a plurality of individual units each independently resilient, and all individually mounted on transverse and longitudinal strips, in which the transverse strips are formed with recesses in the sides thereof, and the longitudinal strips with openings corresponding with said recesses, and the units include base members with posts extending upward through said recesses and openings providing mounting means for springs providing the resilient members of said units, said posts sloping upward and outward and having caps vertically slideable thereon, said caps provided with spring members by which they are held upward.

8. A resilient pad comprising a plurality of individual units each independently resilient, and all individually mounted on transverse and longitudinal strips, in which the transverse strips are formed with recesses in the sides thereof, and the longitudinal strips with openings corresponding with said recesses, and the units include base members with posts extending upward through said recesses and openings providing mounting means for springs providing the resilient members of said units, said posts sloping upward and outward and having caps vertically slideable thereon, said caps provided with spring members by which they are held upward, and the upper ends of said posts provided with slots permitting removing and replacing said caps.

9. A unit for a resilient pad comprising a cap, posts upon which said cap is vertically slideable, said posts sloping outward toward their upper ends and means resiliently holding said cap upward, said unit characterized in that flanges at the upper ends of the posts are provided with slots permitting removing and replacing said caps, with the caps turned to such an angle that lips on the lower ends of said caps pass through said slots to permit removal of said caps from said posts.

45 10. A unit for a resilient pad comprising a cap, posts upon which said cap is vertically slideable, said posts sloping outward toward their upper ends and means resiliently holding said cap upward, said unit characterized in that said posts are mounted upon a common base member and extend through openings and recesses in holding

strips of material positioned at right angles to the strips forming the base, forming a network for holding said caps substantially in engagement, and preventing binding between the caps.

11. A unit for a resilient pad comprising a cap, posts upon which said cap is vertically slideable, said posts sloping outward toward their upper ends and means resiliently holding said cap upward, said unit characterized in that the units are mounted upon a base comprising longitudinal and transverse strips of material with means locating and holding said resilient holding means, and posts to locate said caps in a substantially smooth plane with the sides of the caps substantially in engagement, and preventing binding between the caps.

12. A resilient underpadding for laundry and pressing machines comprising the combination of a plurality of independent caps having means resiliently holding said caps upward, sloping, guiding and limiting means for said caps located at diametrically opposite points, and base members comprising longitudinal and transverse strips of material having means holding said sloping guide members for holding said caps in a relatively smooth plane with the caps substantially in engagement with each other and preventing binding between the caps.

13. A resilient unit comprising a base, a cap, and a spring between said cap and base, with upwardly and outwardly sloping posts extending from said base with grooves in their outer surfaces, and tongues extending from said caps into said grooves and in sliding engagement therewith, said unit characterized by notches in flanges at the upper ends of the posts through which said tongues extending from said caps may pass when assembling said units, with the caps tilted to a relatively sharp angle.

14. A resilient unit comprising a base, a cap, and a spring between said cap and base, with upwardly and outwardly sloping posts extending from said base with grooves in their outer surfaces, and tongues extending from said caps into said grooves and in sliding engagement therewith, said unit characterized by and used in combination with a base for mounting a plurality of said units comprising interlocking strips of material for holding said caps substantially in engagement.

GEORGE W. BRISTOL.
